UNITED STATES PATENT OFFICE.

JOHN C. BRACKETT, OF NEW YORK, N. Y., ASSIGNOR TO INGERSOLL-RAND COMPANY,
OF JERSEY CITY, NEW JERSEY, A CORPORATION OF NEW JERSEY.

COAL-CUTTING MACHINE.

Application filed April 5, 1926. Serial No. 99,953.

This invention relates to mining machines, and more particularly to chain coal cutting machines of the type which are adapted to be propelled by means of cables anchored at their ends and reeled on drums actuated 5 from suitable motors within the machine.

One object of the invention is to enable the machine to be controlled so that either of its cable take-ups or drums may be independently operated from a single source of power. Other objects of the invention are 10 to drive the propelling means flexibly.

The invention will be more clearly understood by reference to the accompanying 15 drawings, in which

Figure 1 is a top view portion of the main casing being shown in section to indicate the arrangement of parts in the interior,

Figure 2 is a side view,

Figure 3 is a cross section along the line 20 3-3 looking in the direction of the arrows,

Figure 4 is a cross section through the main casing along the line 4-4 looking in the direction of the arrows,

Figure 5 is a longitudinal section along the line 5-5 looking in the direction of the arrows,

Figure 6 is a rear end view of the machine showing the arrangement of the controls 30 mounted at the rear of the machine,

Figure 7 is a cross section along the line 7-7 looking in the direction of the arrows,

Figure 8 is a cross section along the line 8-8 looking in the direction of the arrows, 35 and

Figure 9 is a section along the line 9-9 of Figure 2 looking in the direction of the arrows.

Referring to the drawings, the coal cutting machine comprises a main casing A on 40 which there is mounted a second casing B housing an electric motor C. A cutting element D is supported by the casing A and the second casing B preferably rigidly. The coal cutting machine is of the type in which 45 the cutting element or cutter bar D is provided with a travelling chain E provided with suitable teeth F, the chain E being driven by the motor C by means of a worm G on the drive shaft H of the motor C meshing with the worm wheel J on a vertical shaft K extending substantially from top to bottom of the main casing A (Figure 50 3) and provided with a sprocket L over which the chain E passes. In order to en-

gage and disengage the motor C from the vertical shaft K, the clutch O preferably of the jaw type is provided slidably on the vertical shaft K engaging jaws P on the worm wheel J. The upper end of the shaft 60 K is provided with an anti-friction bearing Q seated in a depression R in the upper face of the casing A, a plate or cap S being provided to seal the depression R against the entrance of dust and other foreign matter. The shaft K is packed at the lower face of the casing A by means of a gland T compressing packing material U about the shaft, bolts V being provided to hold the gland T in place.

On the lower face of the main casing A and the motor casing B there is bolted a base or shoe W attached by means of the bolts X to the casing upon which the coal cutter is adapted to drag itself about on the floor. 70 The shoe W is replaceable when worn. An end thrust bearing block Y for the shaft K is suitably mounted on the inner face of the shoe W.

Means are provided to propel the coal cutting machine along the ground including a pair of drums b and c preferably arranged co-axially on opposite sides of the casing A, there being provided a pair of shafts d mounted on the walls of the casing A for the drums b and c to rotate upon. The drums b and c are preferably driven by the fluid actuated motors e and f respectively. The motors e and f are independent of each other each being provided with a similar driving gear to the respective drums b and c consisting of a drive shaft g having a worm h meshing with a worm wheel j on a transverse shaft k having a pinion p engaging an internal gear q formed integrally with the 80 interior of the drum.

The motive fluid for operating the gear motors e and f is pumped under pressure into a supply chamber r by a gear pump s. 100 As shown in Figure 1, the gear pump consists of three sections, t, u and v all operated from the main shaft H of the motor C and each having separate discharge chambers w, x and y respectively. The pump u being of larger capacity than the others, t and v, 105 is arranged to supply motive fluid under pressure to either of the gear motors e and f by means of two way throttle valves 2 and 3 respectively. The gear motor e is provided with two chambers 4 and 5 which may 110

each serve as an inlet or discharge side of the motor *e* depending upon the direction of rotation. The supply chamber *y* may be associated with the gear motor *e* by rotating the throttle valve 2 either with the chamber 5 or with the chamber 4. As shown in Figure 4, whichever of the chambers 4 or 5 is associated with the supply chamber *y* becomes the inlet side of the motor *e* and for the same position of the throttle valve 2 the other chamber 4 or 5 is connected with a discharge passage 6 leading to the sump or chamber 7 acting as a reservoir for the inlet side of the pump *s*. The smaller pumps *t* and *v* are adapted to be connected directly with the motors *e* and *f* at the throttle valves 2 and 3 respectively there being check valves 8 and 9 located between the supply chamber *y* and the auxiliary supply chambers 10 and 11 respectively.

Suitable by-pass valves 12 are provided to connect the sump 7 with the discharge chambers *y*, 10 and 11 so that any section of the pump *s* may be disconnected for the purpose of speed control, their function being to bypass the motive fluid and to remove to a large extent the load from the gear pump. Suitable safety valves 13 which are adjustable and spring pressed valves are arranged to automatically by-pass the motive fluid from the supply passages *y*, 10 and 11 to the sump or reservoir 7 when the pressure reaches a certain predetermined value. The gear pump *s* may be rotated in either direction and to this end the chamber 14, which is normally the discharge chamber when the pump is operating in a clockwise direction, (Figure 4) becomes the inlet chamber and the chamber 15 becomes the discharge chamber when the pump *s* is rotated in a counter-clockwise direction. To this end the chamber 14 is provided with check valves 16 and 17 which are arranged to open and close, connecting the sump 7 or the discharge chamber *y* with the chamber 14 depending upon whether the chamber 14 is functioning as an inlet or a discharge chamber for the pump. Likewise, the chamber 15 is provided with check valves 18 and 19 similar in their function to the check valves 16 and 17 respectively.

The throttle valves 2 and 3 are provided with operating levers or handles 20 and 21 which extend through the rear wall of the casing *A* and are conveniently controlled by the operator. The motor *C* is controlled by any suitable type of electric motor controller having a handle 22 extending through the casing, preferably at the rear wall so as to be convenient to the operator. The by-pass valves 12 are controlled by suitable hand wheels 23 also extending through the casing *A* at the rear (Figure 6). Preferably the motive fluid for operating the gear motors *e* and *f* is an oil or an incompressible liquid.

Oil is preferable since it also acts as a lubricant for substantially all of the working parts of the machine. With the exception of the supply passages *y*, 10 and 11 substantially the entire interior of the casing forms a reservoir or sump for oil to be pumped by the pump *s*. All of the gears within the casing, therefore, are constantly submerged in lubricant and wear is reduced.

In practice, cables are attached to the coal cutting machine as shown in Figure 1, the rope 24 to the drum *c* runs over a pulley 25 at a front corner of the motor casing *B* and its end is attached or anchored at a distant point along the face of the work. A retarding cable 26 runs over a pulley 27 at a rear corner of the main casing *A* and is attached or anchored at a distant point back from the face of the work. The rope 24 which acts as a feed cable is reeled up on the drum *c* while the chain *E* is cutting a kerf in the wall of coal at the floor level. A tension is preferably kept in the retarding cable 26 which, pulling about the pulley 27 as the fulcrum, tends to pull the end of the cutter bar *D* into the coal face. Suitable manipulation of the throttle valves 20 and 21 to rotate the gear motors *e* and *f* in the proper direction and at the proper speed permits the operator to handle the machine to effect under-cutting of the coal face.

The machine above described is particularly suitable for short wall working as is well known in the art of mining. It will be seen that either drum *b* or *c* may be operated in either direction by suitable handling of the reversing throttle valves 2 and 3, by means of their respective controlling levers 20 and 21 while the speed of each may be properly regulated by the by-pass valves 12 without effecting the speed of the motor *C*. Only one electric motor is necessary in this work, the gear pump *s* and the gear motors *e* and *f* being very reliable and of good mechanical efficiency transmit the power of the electric motor *C* to the drums *b* and *c* in a simple and efficient manner and with a great degree of flexibility.

I claim:

1. A coal cutting machine comprising, the combination of a main casing, a cutting element supported by the main casing, a motor in said casing for driving the cutting element, drums arranged co-axially on opposite sides of the casing, a feeding cable on one of said drums, a retarding cable on the other of said drums, fluid actuated gear motors for rotating the drums, and a fluid pump driven by the motor for supplying fluid under pressure to the gear motors.

2. A coal cutting machine comprising, the combination of a main casing, a cutting element supported by the main casing, a motor sealed by said main casing for driving the cutting element, rotatable drums carried by

the casing and arranged co-axially with respect to each other on opposite sides of said casing, cables on said drums, fluid actuated gear motors arranged independently with respect to each other and connected to rotate the drums for winding and unwinding the cables, and a fluid pump connected to be driven by the motor for supplying fluid under pressure for actuating the gear motors.

3. A coal cutting machine comprising, the combination of a main casing, a cutting element supported by the main casing, a motor sealed by said main casing for driving the cutting element, rotatable drums carried by the casing and arranged co-axially with respect to each other on opposite sides of said casing, cables on said drums, individual fluid actuated reversible gear motors for rotating the drums, whereby the drums may be rotated separately and in opposite directions with respect to each other, a pump driven by the motor for supplying fluid under pressure for actuating the gear motors, and a reservoir in communication with said pump.

4. A coal cutting machine comprising, the combination of a casing, a cutting element supported by the casing, a motor sealed in said casing for driving the cutting element, drums arranged co-axially on opposite sides of the casing, cables on said drums for propelling the machine, fluid actuated gear motors connected to rotate the drums for winding and unwinding the cables, an oil pump driven by the motor for supplying oil under pressure to the gear motors, an oil reservoir in said casing associated with the pump, and means between the pump and the gear motors for by-passing oil to the reservoir.

5. A coal cutting machine comprising, the combination of a casing, a cutting element supported by the casing, a motor sealed in said casing for driving the cutting element, drums arranged co-axially on opposite sides of the casing, cables on said drums for propelling the machine, fluid actuated gear motors connected to rotate the drums for winding and unwinding the cables, an oil pump driven by the motor for supplying oil under pressure to the gear motors, an oil reservoir in said casing associated with the

pump, manually operable means between the pump and the gear motors for by-passing oil to the reservoir, and automatic means for by-passing oil from the pump to the reservoir when the oil pressure reaches a predetermined value.

6. A coal cutting machine comprising, the combination of a casing, a cutting element supported by the casing, a motor sealed in said casing for driving the cutting element, drums arranged co-axially on opposite sides of the casing, cables on said drums for propelling the machine, fluid actuated gear motors connected to rotate the drums for winding and unwinding the cables, an oil pump driven by the motor for supplying oil under pressure to the gear motors, an oil reservoir in said casing associated with the pump, manually operable valves between the pump and the gear motors for by-passing oil to the reservoir, and automatic adjustable valves between the pump and gear motors for by-passing oil to the reservoir when the oil pressure reaches a predetermined value.

7. A coal cutting machine comprising, the combination of a casing, a cutting element supported by the casing, a motor sealed in said casing for driving the cutting element, a base supporting the casing, drums arranged co-axially on opposite sides of the casing, a feeding cable on one of said drums, a retarding cable on the other of said drums, fluid actuated reversible gear motors connected to rotate the drums, a fluid pump connected to be driven by the motor for supplying fluid under pressure to the gear motors, a passage providing communication between the pump and the gear motors, an oil reservoir in said casing associated with the pump, hand controlled valves for bypassing oil from the passage to the reservoir, adjustable spring pressed valves for automatically by-passing oil from the passage to the reservoir when the oil pressure reaches a predetermined value, manually operable means for controlling the flow of oil to the gear motors, and check valves in said passage to prevent back pressure through said passage.

In testimony whereof I have signed this specification.

JOHN C. BRACKETT.
